(57) **CLAIM**

We claim the ornamental design for an air register louver, as shown and described.

DESCRIPTION

FIG. 1 is a perspective view of a first embodiment of an air register louver showing our design;
FIG. 2 is a front elevation view thereof;
FIG. 3 is a rear elevation view thereof;
FIG. 4 is a top plan view thereof;
FIG. 5 is a bottom plan view thereof;
FIG. 6 is a left elevation view thereof;
FIG. 7 is a right elevation view thereof;
FIG. 8 is a section view taken from line **8-8** in FIG. 2;
FIG. 9 is a perspective view of a second embodiment of the air register louver showing our design;
FIG. 10 is a front elevation view thereof;
FIG. 11 is a rear elevation view thereof;
FIG. 12 is a top plan view thereof;
FIG. 13 is a bottom plan view thereof;
FIG. 14 is a left elevation view thereof;
FIG. 15 is a right elevation view thereof; and,
FIG. 16 is a section view taken from line **16-16** in FIG. 10. The broken lines shown represent portions of the air register louver that form no part of the claimed design.
